UNITED STATES PATENT OFFICE.

HENRY H. HYDER, OF HOLLYWOOD, CALIFORNIA.

WIRELESS APPARATUS.

1,379,589.

Specification of Letters Patent. Patented May 24, 1921.

Application filed June 5, 1918. Serial No. 238,243.

To all whom it may concern:

Be it known that I, HENRY H. HYDER, a citizen of the United States, and a resident of Hollywood, State of California, have invented a new and useful Improvement in Wireless Apparatus, of which the following is a specification, the principle of the invention being herein explained, and the best mode in which I have contemplated applying that principle so as to distinguish it from other inventions.

The present invention relates to mechanism for mechanically locking an electrical circuit so that it can be closed only upon the closing and opening of another circuit according to a predetermined scale. It is particularly adapted to be used in connection with circuits for exploding mines and the like, the entire device being operated by wireless, the wireless operator knowing the necessary intervals of time for closing and opening the circuit controlling the mechanical lock and operating mechanism for closing the working circuit. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:—

Figure 1 is a diagrammatic view of the circuit connections of the device; Fig. 2 is a top plan view of the mechanical locking means; Fig. 3 is a section taken on the line 3—3, Fig. 2; Fig. 4 is a section on the line 4—4, Fig. 3; and Fig. 5 is a section on the line 5—5, Fig. 2.

The locking mechanism consists of a base member 1 having standards 2 thereon, carrying a housing 7 in which is mounted a lead screw 3, which has one end 4 extending through the bearing, a gear 5 being mounted on said extending end. A carriage 6 is slidably mounted on the housing 7, and in the lower part of the carriage is mounted a mutilated nut 8, which is adapted to engage

with the lead screw 3 to drive the carriage along the same. This mutilated nut has a pin 9 extending downwardly in a slot 10 in the carriage, a spring 11 being mounted in such slot to maintain the mutilated nut in engagement with the lead screw 3. Adjacent one end of the base, and mounted on an extending arm 12 thereof, is a motor 13 carrying a gear 14 on the outer end of its shaft, which gear meshes with a large idler gear 15, which in turn is in mesh with the gear 5 on the shaft end 4 in order to operate the lead screw 3.

The movable carriage is provided with an upwardly extending arm 20 having a horizontal portion 21, to which is pivotally mounted a guide arm 22 normally held in the position shown in Fig. 3 by means of a coil spring 23. On the upper insulation plate 24 of the base are pivotally mounted, two guides 25 and 26 in the path of movement of the guide arm 22. A third guide 27 is mounted parallel to the lead screw 3 and the guide 25 is adapted to be held against the guide 27 by means of a coil spring 28. The guide 26 has one end held against the guide 25 by means of the coil spring 29. Adjacent the motor end of the plate 24 is mounted a spring contact member 30, which is normally spaced from an adjustable contact screw 31, which passes through a block 32, and is provided with a lock nut 33 to hold it in any desired position. When the carriage is moved from the position shown in Fig. 2 to the left, the guide arm 22 is moved along between the guides 27 and 25, forcing the guide 25 outwardly until the arm 22 passes the end 34 of the guide 25. As soon as this movement has been completed, if the carriage is then moved in the opposite direction, the arm 22 will pass along the outer side of the guide 25 until it contacts and forces outwardly the guide 26 and passes therebetween. If the carriage at this time is then moved again to the left, then the guide arm 22 will cam along the outer face of the guide 26 until it strikes the contact member 30, which will force this against the contact screw 31.

Extending laterally from the arm 20 of the carriage is a pin 36, which is adapted to

- contact a resilient arm 37 to move the same away from an adjustable contact screw 38 held by means of a lock nut 39 in a contact bushing 40. The lower part of the carriage 5 is adapted, in the position shown in Fig. 2, to contact a resilient arm 41, which normally is in contact with an adjusting screw 42, held in a contact bushing 43 by means of a lock nut 44.
- 10 In the normal position of the device, that shown in Fig. 2, the switch A, composed of resilient arms 41 and the contact screw 42, will be opened, while the switch B, comprising the arm 37 and the contact screw 38, 15 will be closed, and the switch C, with the resilient arm 30, will be open. As the switch C controls the circuit to be operated, then in order to close this switch it is necessary to move the carriage and the guide arm 20 to the left until it passes the first guide, then to the right until it passes the end of the second guide, and then again to the left until it contacts with and closes the switch C. It will thus be seen that if the motor 25 runs at a constant speed the time necessary for the carriage to be moved past the various guides will be determined to within very close limits, and unless these limits are adhered to the switch C cannot be closed, as 30 movement to the left, beyond the necessary point to pass the guide arm, will open the switch B, which is adapted to open the motor circuit to prevent further forward movement. It will be seen in Fig. 2 that the 35 guide arm will pass along the outer face of the guide 25 in its return movement and will trip over the rear end of the same to return to the normal position at the right, as shown in Fig. 2.
- 40 Turning to the wiring diagram, there is shown the ends of a wireless receiving circuit 50, to which is connected an audion 51, adapted to receive the wireless waves to control the circuit 52, including the battery 53 45 and a relay 54. When energized, this relay 54 actuates the switch 55, which closes a circuit 56 through a battery 57 and a second relay 58. This relay 58, when actuated, closes the switch 59, which actuates the next 50 circuit containing the battery 60 and a relay 61 to close the motor circuit through the switch X. When the device is in its normal position the switch X will be drawn by the spring 62 against the contact 63. This contact 63 is connected by a wire 64 with the battery 65, and the wire 66 to the resilient contact arm 41 of the switch A, which is normally open, and then back through the wire 67, through the reversing relay 68 to 60 the movable switch member X. Whenever the switch X is closed through the contact 69 the motor circuit is closed through the wire 70, the switch B which is normally closed, the wires 71 and 72, the armature 73 65 and the wire 74, through the contact point 75 to one end 79 of the insulated armature of the relay, and thence out through the wire 81, through the motor field 82, the wire 83, the battery 84 through the end 80 of the relay armature, and then through the 70 contact point 76 and the wire 85 back to the movable switch member.
- As soon as the switch X is opened the circuit through the relay and the switch A will be closed, and the armature to the relay will 75 be pulled down, to close the contacts 78, 79, 80 and 77. This, as is readily seen, will reverse the current through the motor armature to move the carriage to the right, as shown in Fig. 2. As soon as the carriage reaches the 80 end of its travel, the switch A will be open, reversing the relay to open the motor circuit.
- The device includes a switch C in circuit with a battery 86 and an induction coil 87 by means of the wires 88 and 90. The other 85 side of the induction coil is connected to a spark gap 89, which will be the working circuit which is adapted to be operated either to explode a mine or to operate any 90 other desired device.
- It will be seen that the carriage must be moved, from the position shown in Fig. 2, forwardly until it just passes the end of the first guide, and then must be reversed until it just passes the end of the second guide, 95 and then again moved forwardly until it contacts with the member 30 to close the switch C. Whenever the switch X is closed through the contact 69 the motor will move the carriage forwardly and this switch X 100 will remain closed as long as the operator of the wireless sending apparatus maintains certain wave lengths through the audion, which will in turn close the relays to actuate the switch X. Thus the operator of the 105 wireless sending apparatus, who knows the lengths of time that it takes the motor to move the carriage forwardly until it just passes the guide, and then the length of time necessary for it to reverse and pass the end of the 110 second guide, is enabled to operate the device through the audion. If someone else tries to operate it, movement of the carriage too far to the left opens the switch B and thereby stops the motor. Then if the switch X 115 is opened, the motor will be reversed and will move back until the switch A is opened which will operate the reversing relay to stop the motor which will remain idle until the switch X is again closed. In its return 120 movement the guide arm trips over the right end of the guide 25 to return to its normal position. It will thus be seen that only by a series of predetermined movements of the carriage can the device be operated to close 125 the working circuit through the contact member 30. The variations in the predetermined movements are unlimited, as more than two guides may be used, and the lengths of these guides may be varied so that any 130

number of different combinations may be worked out.

It is of course understood that the device may be worked by other than a wireless apparatus, it being only necessary to maintain the switch X closed for certain definite periods, with a definite period or periods of opening in between the periods of closing the switch X.

10 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

20 1. In mechanism of the character described, the combination of a movably mounted carriage, a guide arm movably attached thereto, means adapted to actuate said carriage in either direction, and a series of guides interposed between the normal 25 path of said guide arm and a member to be engaged thereby, said guides being adapted to actuate said guide arm into engagement with the member only upon a predetermined series of movements of said carriage.

30 2. In mechanism of the character described, the combination of a movably mounted carriage, a guide arm movably attached thereto, means tending to restrain independent movement of said guide arm, 35 means adapted to actuate said carriage in either direction, and a series of guides interposed between the normal path of said guide arm and a member to be engaged thereby, said guides being adapted to actuate said 40 guide arm into engagement with the member only upon a predetermined series of movements of said carriage.

45 3. In mechanism of the character described, the combination of a movably mounted carriage, a guide arm movably attached thereto, means adapted to actuate said carriage in either direction, and a series of pivotally mounted guides interposed between the normal path of said guide arm 50 and a member to be engaged thereby, said guides being adapted to actuate said guide arm into engagement with the member only upon a predetermined series of movements of said carriage.

55 4. In mechanism of the character described, the combination of a movably mounted carriage, a guide arm movably attached thereto, means tending to restrain independent movement of said guide arm, 60 means adapted to actuate said carriage in either direction, and a series of pivotally mounted guides interposed between the normal path of said guide arm and a member to be engaged thereby, said guides being 65 adapted to actuate said guide arm into en-

gagement with the member only upon a predetermined series of movements of said carriage.

5. In mechanism of the character described, the combination of a movably mounted carriage, a motor for actuating said carriage in either direction, a guide arm movably attached to said carriage, means tending to restrain independent movement of said guide arm, a series of pivotally mounted guides interposed between the normal path of movement of said guide and a member to be actuated thereby, resilient means tending to retain said guides in their normal position, said guides being adapted to move said guide arm into engagement with the member.

6. In mechanism of the character described, the combination of a movably mounted carriage, a motor for actuating said carriage in either direction, a guide arm movably attached to said carriage, means tending to restrain independent movement of said guide arm, a guide mounted to prevent movement of said guide arm in one direction, a guide pivotally mounted adjacent said fixed guide, a second guide pivotally mounted adjacent said first pivoted guide, said guides being adapted to contact with the end of said guide arm to actuate the same in the engagement with a working member upon a predetermined series of movements of said carriage.

7. In a device of the character described, the combination of a working circuit having a normally open contact member, a movably mounted carriage, means adapted to actuate said carriage in either direction, a guide arm movably mounted on said carriage, and guide means disposed between the path of movement of said guide arm and the contact member, said guide means being adapted to actuate said guide arm into engagement with said member to close said working circuit only upon a predetermined series of movements of said carriage.

8. In a device of the character described, the combination of a working circuit having a normally open contact member, a movably mounted carriage, a motor adapted to 115 actuate said carriage in either direction, a guide arm movably mounted on said carriage, and guide means disposed between the path of movement of said guide arm and the contact member, said guide means being adapted to actuate said guide arm into engagement with said member to close said working circuit only upon a predetermined series of movements of said carriage.

9. In a device of the character described, the combination of a working circuit having a normally open contact member, a movably mounted carriage, a reversible motor for actuating said carriage, circuit connections for said motor, switch means operable 125 130

upon limit of movement of said carriage in either direction to stop said motor, a movable guide arm on said carriage, guides mounted between the normal path of movement of said guide arm past said guides and said contact member, said guide means being adapted to actuate said guide arm into

engagement with said contact member to close the working circuit only upon a pre-determined series of movements of said carriage.

Signed by me, this 31st day of May, 1918.

HENRY H. HYDER.
